UNITED STATES PATENT OFFICE.

WILLIAM JAEGER, OF PHILADELPHIA, PENNSYLVANIA.

DESIGN FOR A BRACKET FOR LIGHTING FIXTURES.

Application filed September 10, 1924. Serial No. 10,731. Term of patent 7 years.

To all whom it may concern:

Be it known that I, WILLIAM JAEGER, a citizen of the United States, and a resident of Philadelphia, county of Philadelphia, and State of Pennsylvania, have invented a certain new, original, and ornamental Design for a Bracket for Lighting Fixtures, as shown in the accompanying drawings, in which—

Fig. 1 is a front elevation of a bracket,

without a bobeché, for lighting fixtures showing my new design; and

Fig. 2 is a side elevation of the same, without a bobeché.

I claim:

The ornamental design for a bracket for lighting fixtures substantially as shown.

In witness whereof, I have hereunto set my hand this 1st day of August, 1924.

WILLIAM JAEGER.
